UNITED STATES PATENT OFFICE.

GEORGE ALBERT LYON, OF PHILADELPHIA, PENNSYLVANIA.

BUFFER CONSTRUCTION.

Application filed May 10, 1923. Serial No. 637,933.

To all whom it may concern:

Be it known that I, GEORGE ALBERT LYON, a citizen of the United States, and resident of Philadelphia, county of Philadelphia, State of Pennsylvania, have made a certain new and useful Invention Relating to Buffer Constructions, of which the following is a specification, taken in connection with the accompanying drawing, which forms part of the same.

This invention relates to automobile buffers or bumpers, in which one or more of the adjustably connected buffer front elements may advantageously be formed of relatively wide thin steel strip such as spring steel one and three quarters to two and one-half inches wide and one-fourth to three-eighths of an inch thick, more or less, which may be cut or trimmed away at one or both sides of the strip for six to eight inches more or less to form a narrowed connector portion which may only be one-fourth to one-half of the normal width of the strip, so that this connector portion may be readily bent edge-wise around suitable forms when heated to form an integral connection for the adjacent parts of the vertically or transversely separated strip members which may thus be advantageously vertically or transversely aligned, if desired. A pair of such buffer front elements may be rigidly connected so as to overlap more or less adjacent the connecting or clamping devices and may be laterally adjustable where the width of the buffer front is to be adjusted. Such buffer elements may however be used in other connections as for separate wings or for supporting elements for connection with buffer front elements if desired. It is usually desirable to cut or trim away the connector portion of the strip element on the outer side of its edge-wise bent connector portion which effectively secures a somewhat greater transverse separation between the two connected transversely separated portions or strip members, although in some cases the inner edge-wise bent part of the strip may be preliminarily trimmed or cut away if desired. It is also possible to form distinctive design configurations by such trimming and edge bending methods so that the buffer elements may be given distinctive and pleasing shapes at the buffer ends as well as being securely and integrally connected in this

way. Any suitable form of supporting or attaching devices may be used in connection with the front strips or elements which may sometimes be in the form of a single strip having overlapped or otherwise connected ends and having vertically separated portions joined by two such edge-wise bent connector portions at the ends of the buffer front; and it is usually desirable to have supporting attaching members which may be clamped or connected to both of the vertically or transversely separated strips adjacent the buffer ends so as to give ample support to all of the parts of the buffer front.

In the accompanying drawing showing in a somewhat diagrammatic way a number of illustrative embodiments of the invention—

Fig. 1 is a front view of an illustrative buffer.

Fig. 2 is a top view thereof.

Fig. 3 is a detail view showing a narrowed connector portion of the strip.

Fig. 4 shows the corresponding edge bent connector portion and adjacent transversely separated strips, and

Figs. 5 to 12, show other forms of blank and their corresponding edge bent connector portions.

In the buffer front shown in Figs. 1 and 2 two generally similar elements may be rigidly connected in laterally adjusted position. These elements may be formed of relatively wide thin steel strip and may each comprise two vertically separated substantially horizontally extending front members or strips such as 1, 7, which may be connected at the end of the front element by an edge-wise bent narrowed connector portion located in substantial vertical alignment, if desired, with the adjacent portions of the strips 3, 7, which may be rearwardly inclined as shown in Fig. 2, or the whole buffer front may be forwardly arched or curved, if desired. The other front element may comprise a similar narrowed edge-wise bent portion 5 integrally connecting the adjacent portions 11, 12 of the strip which may be inwardly extended so as to overlap the vertically spaced strips of the other element at least adjacent the clamping or connecting devices such as 14. In each element one of the vertically spaced strips such as 12 may be relatively shorter so that its end 13 extends slightly past the end 2 of the longer strip of the other element while

the long lower strip 9 may have its end 10 located in somewhat overlapping position above the end 8 of the short strip 7 of the co-operating buffer front element. Any desired form of supporting attaching devices may be used with such a buffer front and a brace bar type of spring steel strip supporting device may be used comprising the laterally extending brace bar portion 19 adapted to 5 be connected to the frame ends 20. Forwardly curved portions such as 18, 21, and 23 may give a greater resilient yield to the supporting members which preferably have inturned connecting portions 13, 15 to be 10 clamped to the buffer front strips adjacent or preferably within a foot or so of the ends of the buffer front, preferably so as to overlap both the upper and lower vertically separated strips at the clamping devices such as 15 20, 14, to which they may be connected by the clamping bolts 17. This arrangement provides several inches at least of lateral adjustment of the buffer front elements to suit different width automobiles and the front 25 strips may be rigidly connected in adjusted overlapping position so as to securely hold all of the buffer parts under collision and running conditions.

As shown in Fig. 1, the integral connector 30 portions 5 may be edgewise bent and by preliminarily cutting away the steel strip on the outer side of this edgewise bend, the bend is made very much more easily and the ornamental curved or reduced portions 35 4, 6 may be formed adjacent the bent connector portion at the end of the buffer front element so as to give not only a strong connection but a pleasing and finished appearance to the buffer ends, the inner edges 58 40 of the adjacent strips being separated one to one and one-half inches or more, as desired. One way in which this may be done is illustrated in Figs. 3 and 4 where the buffer front strip is shown as having a 45 curved or crescent shaped cut out portion 24 so as to form a considerably narrowed connector portion 25 which may be no more than a third or a quarter of the normal width of the strip in some cases. Then this 50 part of the front strip or the entire length thereof, if desired, may be brought up to a good high bending heat and then the connector portion may be bent around suitable forms, if desired, so as to form this edgewise 55 bent connector portion indicated in Fig. 4. If desired, the edgewise bent connector portion may be in substantial vertical alignment with the adjacent portions of the connected buffer front strips which may be vertically separated and, if desired, rigidly held in substantial vertical alignment adjacent the end of the element, the opening 26 between the adjacent edges of the vertically spaced strip members being 60 made one to four inches, as desired, and the 65 shape of the cut out portion being regulated accordingly so as to give the desired contour to the end of the buffer element and produce, if desired, the pleasing concave edges 4, 6. Another blank is shown in Fig. 5 as 70 having a narrowed connector portion 30 formed by the curved cut out portion 28 which is more nearly straight at the ends of the cut 29 adjacent the full width portions 27, 31 of the thin wide strip. Thus when 75 the narrowed connector portion is edgewise bent by hot or cold bending processes, this narrowed connector portion 30 may be bent into curved or circular form as in Fig. 6, and be joined by the relatively straight inclined edges 29 with the adjacent full width portions 27, 31 of these vertically separated buffer strips. Of course these buffer elements which may be used for buffer fronts or supporting elements, as desired, may advantageously be heat treated as by oil quenching and tempering at any suitable part of the process, preferably at the same heat as used for bending and shaping the element where this additional resilient 80 strength and stiffness is desired.

Many other distinctive and ornamental design configurations may be produced by such edge bending processes after cutting out one or both edges of the buffer strip adjacent the narrowed edge bent connector portion, and Fig. 7 shows one form of blank in which the connector portion 36 may be narrowed to about a quarter of the normal 85 width of the buffer strip, if desired, the cut out edge being formed with a gradually curving portion 35 joined by the curved recesses 34, 38 with the somewhat angular portions 33, 39 adjacent the full width parts of the strip 32, 40. This narrowed connector 90 portion may be bent edgewise around suitable forms, if desired, so as to form a distinctively shaped buffer end shown in Fig. 8, in which this narrowed connector portion is edgewise bent into somewhat arched form 95 with the rather elliptical inner and outer curved edges 37, 35 while the curved or angular edges 33, 34 and 38, 39 form cooperating projections more or less in line with these vertically separated upper and lower 100 front strips 32, 40. Of course these projections may be given other distinctive forms for special purposes and preferably the narrowed connector portions of the steel strip 105 may be blanked out in cutting dies of corresponding form so as to produce and more or less finish, if desired, these narrowed connector portions which may be readily bent and yet furnish ample strength to support 110 the adjacent portions of the buffer strips, especially where the buffer front strips are both supported adjacent this connector portion as by clamping or securely connecting them to the supporting strips or other 115 clamping devices within six to sixteen 120

125

130

inches of the edgewise bent narrowed connector portion of the strip.

Fig. 9 shows another form of narrowed connector portion in which a semi-circular or rounded projection 46 may be left adjacent the connector portion 44 where the strip is to be edgewise bent and curved portions or cut edges 50 may join this mid portion of the narrowed connector with the full width portions 41, 49 of the wide flat steel strip. Such a blank may, for instance, be edgewise bent as indicated in Fig. 10 so as to give a considerably wider separation between the transversely separated strips 41, 49, the inner edge of this bend being formed with two curved portions or inner edges 45; if desired, while a comparatively straight inner edge is formed opposite the rounded edge projection 46 which may form the end of this buffer front element, if desired. The bending may produce the curved portions 42, 43 and 47, 48 of pleasing contour, the blank being cut out so as to give these edge configurations with the particular bending heats and forms employed. Fig. 11 shows a simpler form of blank having one edge cut out to form a narrowed connector portion 55 where the cut out edge 53 is comparatively straight and joined by the curves 52, 54 with the adjacent full width parts of the strip. After bending this narrowed connector portion edgewise preferably around suitable forms while at least this part of the strip is heated, substantially semi-circular curved edges may be formed on the inner edge 56 and the outer edge 52, 53, 54 of this connector portion 55, as shown in Fig. 12, which gives a strong and pleasing integral connection to these buffer strips which may be used for buffer front elements with advantage. By suitably narrowing the blank preferably, but not necessarily, on the edge of the wide strip which forms the outside edge of the bent connector portion, good strong bends having pleasing curved edges may be formed so as to secure transverse separation between the adjacent edges of these connected buffer strips of no more than an inch or an inch and a half, if desired, for special purposes.

This invention has been described in connection with a number of embodiments, forms, proportions, sizes, parts, arrangements, materials, methods of construction, connection and use, to the details of which disclosure the invention is not of course to be limited, since what is claimed as new and what is desired to be secured by Letters Patent is set forth in the appended claims.

I claim:

1. The automobile buffer comprising a pair of adjustably connected elements formed of wide thin steel strip and each having vertically spaced substantially vertically aligned horizontally extending por-

tions of different lengths and an integral edgewise bent narrowed connector portion at the end of the element, and steel strip supporting members having laterally extending inturned ends rigidly secured to both vertically separated portions of said elements in overlapping position therewith adjacent the ends of the buffer front and adapted to be secured to the automobile frame members.

2. The automobile buffer comprising connected elements formed of wide thin steel strip and each having vertically spaced substantially vertically aligned horizontally extending portions of different lengths and an integral edgewise bent narrowed connector portion at the end of the element, and steel strip supporting members having laterally extending inturned ends rigidly secured to both vertically separated portions of said elements.

3. The automobile buffer comprising a pair of adjustably connected elements formed of wide thin steel strip and each having vertically spaced horizontally extending portions and an integral edgewise bent narrowed connector portion at the end of the element, and steel strip supporting members having laterally extending inturned end portions rigidly secured to both vertically separated portions of said elements adjacent the ends of the buffer front and adapted to be secured to the automobile frame members.

4. The automobile buffer comprising a pair of adjustably connected elements formed of wide thin steel strip and each having vertically spaced portions and an integral edgewise bent narrowed connector portion at the end of the element, and steel strip supporting members having laterally extending portions secured to both vertically separated portions of said elements adjacent the ends of the buffer front and adapted to be secured to the automobile frame members.

5. The automobile buffer comprising two laterally adjustable rigidly connected elements formed of wide thin steel strip and each having vertically spaced horizontally extending portions and an integral edgewise bent narrowed transverse connector portion in substantial vertical alignment therewith and formed by removing the outer edge of the steel strip adjacent the edgewise bend to form a narrowed portion less than half the normal width of the strip and a plurality of supporting members formed of flat steel strip and rigidly connected to said elements adjacent the ends of the buffer front.

6. The automobile buffer comprising two laterally adjustable rigidly connected elements formed of wide thin steel strip and each having vertically spaced horizontally extending portions and an integral edge-

wise bent narrowed transverse connector portion in substantial vertical alignment therewith and supporting members formed of flat steel strip and rigidly connected to said elements adjacent the ends of the buffer front.

7. The automobile buffer comprising two connected elements formed of wide thin steel strip and each having vertically spaced 10 horizontally extending portions and an integral edgewise bent narrowed transverse connector portion in substantial vertical alignment therewith and supporting members connected to said elements adjacent the ends of the buffer front.

8. The automobile buffer comprising two connected elements formed of wide thin steel strip and each having vertically spaced portions and an integral edgewise bent narrowed transverse connector portion and supporting members connected to said elements adjacent the ends of the buffer front.

9. The automobile buffer formed of wide thin steel strip and comprising vertically 25 spaced horizontally extending portions and an integral edgewise bent narrowed connector portion of the strip at each end of the buffer front holding the adjacent vertically displaced portions in substantially vertically aligned position and a plurality of supporting members connected to both the upper and lower front strips adjacent the opposite ends of the buffer front and adapted to be secured to the automobile 30 frame members.

10. The automobile buffer formed of wide thin steel strip and comprising vertically spaced horizontally extending portions and an integral edgewise bent narrowed connector portion of the strip at each end of the buffer front and supporting members connected to the front strips adjacent the opposite ends of the buffer front and adapted to be secured to the automobile frame members.

11. The automobile buffer front formed of wide thin steel strip and comprising vertically spaced horizontally extending portions and an integral edgewise bent narrowed connector portion of the strip not 50 more than half the normal strip width at each end of the buffer front holding the adjacent vertically spaced portions in substantially vertically aligned position.

12. The automobile buffer front formed of wide thin steel strip and comprising vertically spaced portions and an integral edgewise bent narrowed connector portion of the strip at each end of the buffer front holding the adjacent vertically spaced portions in substantially vertically aligned position.

13. The automobile buffer front comprising two laterally adjustable rigidly connected elements formed of wide thin steel strip and each having vertically spaced horizontally extending portions and an integral

edgewise bent narrowed transverse connector portion in substantial vertical alignment therewith and formed by removing the outer edge of the steel strip adjacent the edgewise bend to form a narrowed portion less than half the normal width of the strip.

14. The automobile buffer front comprising two rigidly connected elements formed of wide thin steel strip and each having vertically spaced portions and an integral edgewise bent narrowed transverse connector portion in substantial vertical alignment therewith.

15. The automobile buffer front formed of wide steel strip and comprising vertically spaced portions and an integral edgewise bent narrowed connector portion of the strip at each end of the buffer front holding the adjacent vertically spaced portions in substantially vertically aligned position.

16. The automobile buffer front formed of wide steel strip and comprising vertically spaced portions and an integral edgewise bent narrowed connector portion of the strip at each end of the buffer front.

17. The automobile buffer front element formed of wide thin steel strip and comprising vertically spaced horizontally extending portions and an integral edgewise bent connector portion of the strip formed by removing the outer edge portions of the strip adjacent the edgewise bend to form a narrowed portion, less than half the normal width of the strip, holding the adjacent vertically spaced portions in substantially vertically aligned position.

18. The automobile buffer front element formed of wide thin steel strip and comprising vertically spaced horizontally extending portions and an integral edgewise bent connector portion of the strip formed by removing edge portions of the strip adjacent the edgewise bend to form a narrowed portion holding the adjacent vertically spaced portions in substantially vertically aligned position.

19. The automobile buffer front element formed of wide thin steel strip and comprising transversely spaced horizontally extending portions and an integral edgewise bent connector portion of the strip formed by removing the outer edge portion of the strip adjacent the edgewise bend to form a narrowed portion less than half the normal width of the strip holding the adjacent transversely displaced portions in substantially transversely aligned position.

20. The automobile buffer front element formed of wide thin steel strip and comprising transversely spaced portions and an integral edgewise bent connector portion of the strip formed by removing the outer edge portion of the strip adjacent the edgewise bend to form a narrowed portion holding the adjacent transversely spaced portions in

substantially transversely aligned position.

21. The automobile buffer element formed of wide thin steel strip and comprising transversely spaced portions and an integral edgewise bent connector portion of the strip formed by removing the edge portion of the strip adjacent the edgewise bend to form a narrowed portion holding the adjacent

transversely spaced portions in substantially transversely aligned position. 10

22. The automobile buffer element formed of wide thin steel strip and comprising transversely spaced portions and an integral narrowed edgewise bent connector portion of the strip.

GEORGE ALBERT LYON.
